ASST. CLERK.

UNITED STATES PATENT OFFICE.

AUSTIN FREDERICK JACKSON, OF TAUNTON, MASSACHUSETTS, ASSIGNOR
TO REED & BARTON, OF SAME PLACE.

DESIGN FOR A HANDLE FOR KNIVES, FORKS, SPOONS, &c.

SPECIFICATION forming part of Design No. 17,008, dated November 30, 1886.

Application filed October 20, 1886. Serial No. 217,636. Term of patent 7 years.

To all whom it may concern:

Be it known that I, AUSTIN FREDERICK JACKSON, of Taunton, in the county of Bristol and State of Massachusetts, have invented and produced a new and original Design for Handles for Knives, Forks, Spoons, &c., of which the following is a specification, reference being had to the accompanying photographic illustrations, forming part thereof, in

to which—

Figure 1 is a front or upper and Fig. 2 a back or underneath view of the design.

This design is for flat solid handles, and its upper and lower faces present different configuration, as follows: The handle in outline is widest at its butt-end and tapers gradually to the narrow shank, the edges being, however, made to deviate from a straight line by a slight swell at *a* and a slightly-waved edge at *b*, near the shank. On the front of the handle there is struck up in relief a face or mask, *a'*, with a head-gear, *a'*, descending to the swelled edges *a* *a*. Adjoining this is a bib-like drapery or scapular, *c*, with a fruit piece for a central figure, surrounded by a border of tuberoses, *c'*. Adjoining this is a narrow panel, *d* *d*, with background of parallel transverse lines, with a spray of flowers in the middle and an overlapping border of tuberoses.

30 Between the waved edges *b* *b* are scrolls *b'* and

ornamental cross bands *b''*, and between these and the fork-tines the shank has longitudinal parallel ridges *b'''*. On the under side of the handle, at the butt-end, there is a plain oval escutcheon, *e*, with a scrolled ornament, *e'*, at the top and another, *e''*, at the bottom. At the waved portion *b* there is an outline figure of a lyre, *f*, partly covered by scrolls.

What I claim is—

1. In a design for a knife, fork, spoon, &c., the handle having a tapered outline, with a swell at *a* and waved edges *b*, the face or mask *a'*, with head-gear *a'*, the scapular *c*, with fruit piece for central figure and border of tuberoses, the panel *d*, with spray of flowers in the center and overlapping border of tuberoses, scrolls *b'*, transverse bands *b''*, and parallel longitudinal ridges *b'''*, substantially as shown and described.

2. In a design for a knife, fork, spoon, &c., the handle having a tapered outline, with swell at *a* and waved edges *b*, with an oval escutcheon, *e*, at the outer extremity, having scrolled ornaments *e' e''* at top and bottom, and a lyre-shaped figure and scroll, *f*, at the waved edges, substantially as shown and described.

AUSTIN FREDERICK JACKSON.
